UMBRELLA

Herman H. Feller, Brooklyn, N. Y.

Application February 3, 1939, Serial No. 254,342

2 Claims. (Cl. 135—34)

This invention relates to improvements in umbrellas and has as an object the provision of umbrellas having removable covers whereby the covers may readily be replaced, if damaged, or if covers having different designs or colors are desired.

Umbrellas of the type now commonly used are provided with covers that are permanently secured to the umbrella frame so that upon damage to the cover, the umbrella is either rendered useless or requires a skilled workman to repair it. Such covers are usually retained on the frame by peripherally located tip members that are secured to the outer ends of the ribs of the umbrella and by means of a ferrule engaging the center of the cover which is permanently secured to the umbrella stick. Additionally, the covers may be secured at one or more places along each of the ribs by stitching or tacking. Thus to replace the covering of this type of umbrella, it is necessary to detach a number of permanently secured parts before the cover can be removed and to replace the parts permanently after the new cover is placed upon the frame.

The present invention provides an umbrella construction in which the edges of the cover are readily releasable from the ribs and the ferrule on the umbrella stick is detachably connected thereto so that these elements may be readily released and the cover removed therefrom and a new cover easily substituted. Preferably, the ferrule is connected to the stick by means of a latch or lock which may be quickly released to allow removal and replacement of the cover. Likewise, the rib tips may be frictionally or otherwise detachably secured to the ribs so that they can be disengaged from the ribs to free the edge of the cover from the frame, or the rib tips may be permanently secured and means provided for detachably connecting the cover to these tips.

Umbrellas embodying the present invention have many advantages not present in prior types of umbrellas. For example, they may be supplied as a kit consisting of an umbrella frame and a plurality of differently designed and colored covers, thereby allowing the color scheme of the umbrella to be changed to complement rather than clash with the ensemble of the user. They likewise admit of inexpensive replacement of the cover, inasmuch as the replacement cover can be supplied at materially less cost than the entire cost of the umbrella. Such covers may be made from a variety of materials, such as for example, silk or cotton fabrics, synthetic rubber or cellulosic films, such as "Pliofilm" or "Cello-

phane," thus fulfilling all requirements as to cost, appearance and durability. Likewise, the replaceable covers lend themselves to a variety of striking effects, such as the use of rib tips of a design matching or carrying out the design on the cover itself. By way of example, a covering having a design of tropical fish might well be provided with rib tips shaped like tropical fish or sea horses and colored appropriately to complement the cover. Other covers bearing different designs and having complementary rib tips may likewise be supplied thus permitting wide variation in the appearance of the umbrella.

For a better understanding of the present invention, reference may be had to the accompanying drawing in which:

Figure 1 is a perspective view of an umbrella embodying the present invention;

Figure 2 is an enlarged perspective view of an umbrella rib and an associated rib tip;

Figure 3 is an enlarged view of the ferrule and a portion of the umbrella stick disclosed in Figure 1;

Figure 4 is a transverse sectional view of a form of ferrule embodying the invention and umbrella stick; and

Figure 5 is an enlarged perspective view of a modified form of device for detachably connecting the periphery of the umbrella cover to the ribs.

The form of the invention illustrated in Figures 1, 2 and 3, consists of a conventional umbrella frame including a stick 10 which may be made of metal, wood, or synthetic plastic material, as may be desired, upon which are pivotally mounted a plurality of cover spreading ribs 11. The ribs may be erected or spread by the usual spreader ribs and sliding ferrule which are not shown since they are conventional and do not constitute a part of the invention. A detachable cover 12 is supported on the stick and the ribs by means of the detachable ferrule 13 and the detachable rib tips 14, the cover 12 being otherwise unsecured to the frame.

As shown in Figure 2, the rib tips 14 may be attached to the cover 12 by thread 15 or any other suitable means and are frictionally received on the ends 16 of the ribs 11. The tips 14 are so located on the cover 12 as to require the cover to be stretched slightly in order to allow the tips 14 to be attached to or detached from the ribs, thereby preventing inadvertent detachment of the cover. The inner ends of the tips 14 may be slightly beveled as at 17 to facilitate insertion of the rib ends 16 into the bores 18 of the tips.

As shown in Figures 1, 3 and 4, the detachable ferrule consists of a generally cup-shaped member 30 having a peripheral groove 31 therein in which is disposed a bent spring 32 encircling the ferrule. The ferrule 30 is provided with an aperture 33 into which one end 34 of the spring 32 is bent to prevent its rotation and which slidably receives the other end 35 of the spring. The bent end 35 is of sufficient length to extend 10 through the ferrule 30 and into an annular recess 36 encircling the stick 37 to lock them together, and is normally urged outwardly by an uncurved portion 38 of the spring 32. The end 35 of the spring 32 may be forced in the recess 36 15 by means of a split ring or sleeve 39, which is rotatably mounted on the ferrule 30 or released by rotating the sleeve to the position shown in Figure 4.

Many different means for detachably connecting the cover to the ribs may be used. As shown 20 in Figure 5, the rib tips 50 may be permanently or semi-permanently attached to the ends of the ribs 51, for example, by means of screw threads or adhesive, and the cover detachably 25 connected to the rib tips. In this form of device the cover 52 may have a series of small grommets or eyelets 53 in its edge which may be passed over the ends of the tips 50 and brought 30 into engagement with shoulders or flanges 54 on the tips 50 which prevent the cover from sliding upwardly along the ribs.

The ferrule 13 and the devices for attaching the edge of the cover to the ribs may be used in any desired combination to permit replacement 35 of the covers. To remove the cover, the umbrella should be closed and the edge of the cover detached first from the ribs. The ferrule may

then be removed and the cover slipped off and a different cover placed on the stick. The ferrule is then attached to the end of the stick and the edge of the cover attached to the ends of the ribs by slipping the tips onto the ends of the ribs 5 or the grommets over the tips.

From the foregoing description, it will be understood that the shape and design of the ferrule is susceptible to considerable modification without departing from the invention and that 10 the form of the invention disclosed should be considered as illustrative, only, and not as limiting the scope of the following claims.

I claim:

1. A device for detachably securing a cover to 15 an umbrella stick comprising a ferrule having an aperture therein, a spring ring on said ferrule having an inturned portion disposed in said aperture, a member rotatably mounted on said ferrule and engageable with a portion of said spring 20 ring to force said end through said aperture and means forming a recess in said stick for receiving a portion of said end and locking the ferrule to said stick.

2. A device for releasably retaining a cover on 25 an umbrella stick and frame comprising a ferrule receivable on the end of the stick and having an aperture in a side wall, a spring member mounted on said ferrule and having an inturned end portion disposed in an aperture in said fer- 30 rule, a member mounted on said ferrule and rotatable to force said end portion through said aperture, and means forming a recess in said stick for receiving said end portion to latch the ferrule to said stick. 35
